Patented Jan. 25, 1921.

UNITED STATES PATENT OFFICE.

ARVID GUSTAFSON, OF BONITA, AND JAMES HENRY MURPHY, OF PORTLAND, OREGON.

CAMPER'S STEEL PORTABLE FOLDING BED.

1,366,728.

Specification of Letters Patent. Patented Jan. 25, 1921.

Application filed July 8, 1920. Serial No. 393,789.

To all whom it may concern:

Be it known that we, ARVID GUSTAFSON and JAMES H. MURPHY, citizens of the United States, and residents of Bonita, in the county of Malheur, and Portland, in the county of Multnomah, respectively, State of Oregon, have invented certain new and useful Improvements in Campers' Steel Portable Folding Beds, of which the following is

10 a specification.

This invention relates to beds of the type adapted and intended for temporary use and for frequent assembling and disassembling and transportation as in camping. It 15 embodies a structure made principally of steel and is so designed that the requisite strength and rigidity may be secured by the use of parts of minimum size and weight while furnishing the user with substantially 20 all of the ease and comfort of an ordinary bed. It includes novel features of construction by which the flexible bed bottom, which may include elasticity, is supported under proper tension to avoid sagging by a minimum of easily attachable and detachable 25 parts. It avoids entirely the use of nuts and screws and other fastening means requiring tedious operations and substitutes quick detachable connections which practically 30 require nothing more than placing the parts in proper relative position. The connections are so formed however that when the parts are assembled there is no possibility that they will become loose or not operate as 35 desired. The easily detachable supporting parts are of such length and shape that they may fit together across the flexible bed bottom parallel to the end bars or angle irons and be rolled up into a small neat roll or 40 package which may be easily handled in transportation as in going from one camp to another. The novel features will be more fully understood from the following description and claims taken with the accompanying 45 drawings.

In the drawings:

Figure 1 is a perspective view of a bed embodying the invention set up ready for use;

Fig. 2 is a perspective view of the parts 50 disassembled and rolled up in the bed bottom ready for transportation;

Fig. 3 is a perspective view of one of the castings which is to be riveted or secured to the angle bar at the head of the bed provided with sockets to make slip joint con-

nections with the supporting posts or legs and with the side rails;

Fig. 4 is an end view of the casting shown in Fig. 3 with sections of pipe in the sockets and the angle bar in dotted lines; 60

Fig. 5 is a plan view of the casting detached looking down with part of a side rail in its socket;

Fig. 6 is a side view of a casting adapted to be secured or riveted to the angle bar at 65 the foot of the bed, shown in dotted lines, and having a downwardly inclined cylindrical projection which forms part of a slip joint in supporting the angle bar and with means for connection to a tension strap, 70 shown in dotted lines;

Fig. 7 is a front view of the casting shown in Fig. 6;

Fig. 8 is a side view partly broken away of the lower section of a side rail with its 75 attached supplemental supporting bar.

Fig. 9 is a cross section on the line 9—9 of Fig. 8;

Fig. 10 is an end view of the supplemental bar shown on a level with it in Fig. 8, and 80

Fig. 11 is a view looking down on the broken away upper end of the lower section of the side rail taken at right angles to the position shown in Fig. 8.

The flexible bed bottom 10 may be made 85 of any suitable fabric but a steel wire fabric is preferred and it of course may be made in any of the well known ways. It is preferable that the bed bottom shall have a capacity for yielding or giving for the comfort of the user and therefore in Fig. 1 a series of coiled springs 11 are shown as interposed between and connecting at intervals the fabric 10 and the transverse angle bar 12 at the head of the bed. As shown 95 one end of each spring passes through a hole or opening 13 in the horizontal flange 14 of the angle bar 12 and is thus securely held. The angle bar 12 has a depending flange 15 at right angles to flange 14 and is 100

preferably made of steel and thus furnishes a continuous rigid connection for the end of the bed bottom. A similar angle bar 16 is used at the foot of the bed having the horizontal flange 17 to which the fabric of the bed bottom is secured through holes 18 and a downwardly extending flange 19. Two castings 20 (see Fig. 3) are secured to the under surface of flange 14 of the end bar 12 near the ends by screws or prefer- 110

ably rivets passing through the openings 21 in the casting and openings 22 in the flange and therefore constitute a permanent part of the angle bar 12. End casting 20 has a downwardly extending cylindrical socket 23 (see dotted lines Figs. 3 and 5) open at the bottom to receive the upper end of a tubular post or leg 24 for supporting the bar 12 and consequently that end of the bed. The upper end of post 24 fits easily in the socket with a slip joint and may be easily removed after lifting the angle bar 12 but any weight on the bed in use simply tends to make the connection more certain and sure. Each casting 20 also has in it an open ended cylindrical socket 25 directed horizontally toward the foot of the bed and adapted to receive in it the end of the upper section 26 of the tubular side rail 27. There is a groove or depression 28 in the face of casting 20 across the open end of socket 25 and a pin 29 extends through the end of section 26 of the side rail fitting in that groove when the end is in slip joint connection with the socket thus preventing the side rail from turning in the socket. Since the casting and socket are rigid with the end bar 12 the side rail can not turn without the turning of the entire bed. The side rail 27 furthermore extends downwardly at an angle to a point below the foot of the bed and any weight on the bed in addition to the normal tension on the bed bottom tends to force it home and hold it there in the socket connection to the end bar and avoids any possibility of the connection coming loose and avoiding all necessity for fastening it otherwise. The tubular side bars 27 are made up of two sections 26 and 30 having quick detachable slip joint connection at the middle so that they may be taken apart for packing the bed and will not be too long to lie within the bed bottom transversely. The slip joint connection between the sections 26 and 30 may be of any suitable kind familiar to those skilled in the art but in Fig. 1 there is shown in dotted lines a form which may be used embodying a cylindrical plug 31 fitting in and projecting from the lower end of section 26 and held therein by a transverse pin 32. The projecting end telescopes with and closely fits the upper end of the lower section 30. Relative rotation of the two sections is prevented by notches 33 in the upper end of 30 engaging pin 34 extending through plug 31. It will be noted in this instance also the normal tension of the bed or that added by weight tends to make the connection tighter and more certain while on the removal of tension the parts separate with the greatest ease by a mere pull.

It will be noted that the lower section 30 of each side rail is bent downwardly at the extreme lower end 35 although the side rails 65 are otherwise straight. A supplemental sup-

porting member or bar 36 is pivoted to the lower section of each side rail at a point not far from the foot of the bed and in use is adapted to extend upwardly at an angle from its pivoted forward end to the end angle bar 16 of the bed as seen in Fig. 1. This supplemental bar is curved transversely over the top portion in the arc of a circle fitting the upper portion of section 30 of the side rail but having a bottom opening 75 throughout most of its length as large as the diameter of the circle on which it is curved as shown in Fig. 9 so as to closely fit the tubular part 30. At its upper or forward end bar 36 is cut away at the top having 80 projecting side ears or flanges 37 which are connected to section 30 by a pivot pin 38 thus permitting upward turning of bar 36. At the extreme end of the supplemental bar 36 and where the section 30 is bent out of the way as shown in Fig. 8 the lower side edges of 36 are turned in toward each other so as to leave a bottom opening of less width than the diameter of the circle on which it is bent and the extent of this bending is indicated in dotted lines in Fig. 8. Fig. 10 shows an end view of the lower edges 39 bent in beyond the outer margin of the opening above. The purpose of this in-bending is to make the end of bar 36 fit and 95 grip the downwardly inclined cylindrical projection 40 on the casting 41 which is secured to the angle bar 16 at the foot of the bed. The casting 41 preferably has side flanges with holes 42 therein and through 100 these holes is bolted or preferably riveted to the flange 19 of the end bar 16. The casting 41 may furthermore have in it a slot 43 through which a flexible connection such as a strap 44 may extend and that 105 strap may extend down to the lower end of the side rails and make connection therewith through a link 45. The purpose and function of this strap is of course to exert tension to pull the angle bar 16 and the lower ends of the side rails together and by the consequent down turning tendency of the supplemental bars 36 to put tension on and keep tight the flexible bed bottom. It 110 should be understood however that the present invention is not limited to the particular means for connecting the angle bar at the foot of the bed to the side rails since various means for doing this adjustably to vary the tension at will will be obvious to 115 those skilled in the art.

It is believed that the steps to be followed in assembling the bed ready for use and those to be followed in disassembling it and rolling up all loose parts in the flexible bed 120 bottom will be obvious from the above description of the structure. By releasing strap 44 the foot bar 16 may be raised breaking the slip joint connection to bars 36 and those bars will fold down on section 130

30 of the side rail. That section may then be separated from section 26 by a mere pull and 26 may be separated from angle bar 12 by a mere pull. The legs or posts 24 may 5 then be pulled out and all the loose articles arranged parallel across the flexible bed bottom and rolled up therein as shown in Fig. 2. This operation is reversed in assembling and is almost as easy. It is believed that one of the essentially novel and 10 useful features of this invention is that it does away with nuts and screws and other complicated fastenings and makes the operation of assembling and disassembling so 15 easy. It is also believed to be new to provide efficient supporting means for the bed bottom which can be quickly detached and rolled up transversely of the bed bottom.

Having thus described our invention what 20 we claim as new and desire to secure by Letters Patent is:

1. A camp bed having quick detachable supporting parts adapted to be rolled up in the flexible bed bottom comprising a flexible 25 bed bottom, rigid transverse end bars to which said bottom is secured, two downwardly extending legs detachably secured to one end bar near its ends by vertical slip joints, two longitudinal side rails at the 30 margin of the bed bottom having detachable slip joint connection operating through longitudinal movement of the side rails with said end bar to which the legs are attached and extending downwardly at angle to approximately the other end of the bed bottom 35 and foldable means carried by said side rails and adapted to be detachably connected by slip joints at their upper ends to said other end bar immediately adjacent its ends to 40 support it and through it apply tension to the bed bottom.

2. A camp bed having quick detachable supporting parts adapted to be rolled up in the flexible bed bottom comprising a flexible 45 bed bottom, rigid transverse end bars to which said bottom is secured, one of said end bars having downwardly extending sockets for slip joint connection with supporting legs and longitudinally extending sockets 50 for slip joint connection with side rails at its ends and the other end bar having, at its ends on the bed bottom side, projections extending downwardly at an angle for slip joint connection with the ends of supporting 55 bars, supporting legs detachably fitting by slip joint in said downwardly extending sockets in said first mentioned bar, side rails detachably fitting at one end by slip joints in said longitudinal sockets and terminating 60 approximately under the ends of the other end rail, supporting bars pivoted at one end to said side rails near their lower ends and having slip joint connection with the downwardly extending projections on said second 65 end bar and adjustable tensioning means

connecting said second end bar to the lower ends of the side rails.

3. A camp bed having quick detachable supporting parts adapted to be rolled up in the flexible bed bottom comprising a flexible bed bottom, rigid transverse end bars to which said bottom is secured, one of said end bars having downwardly extending sockets for slip joint connection with supporting legs and longitudinally extending 70 sockets for slip joint connection with side rails at its ends and the other end bar having, at its ends on the bed bottom side, projections extending downwardly at an angle for slip joint connection with the ends of supporting bars, supporting legs detachably fitting by slip joint in said downwardly extending sockets in said first mentioned bar, side rails detachably fitting at one end by slip joints in said longitudinal sockets and 75 terminating approximately under the ends of the other end rail, supporting bars pivoted at one end to said side rails near their lower ends and having slip joint connection with the downwardly extending projections 80 on said second end bar and adjustable tensioning means connecting said second end bar to the lower ends of the side rails, the said supporting bars being turnable on their pivots to folded position along and close 85 against the lower portion of the side rails, and means embodying a slip joint operable longitudinally for separating the upper and lower portions of the side rails near the middle above the pivot connection to the supporting bars. 95

4. A camp bed having quick detachable parts comprising a flexible bed bottom, rigid end bars of angle iron each having a horizontal flange to the edge of which the bed 100 bottom is connected and a depending outer flange, castings secured to the end bar in the angle between its flanges at the head of the bed near its ends and provided with vertical slide sockets for legs and slide sockets facing 105 longitudinally of the bed for side rails, vertical legs detachably fitting in said vertical sockets, side rails detachably fitting at one end in said longitudinal sockets separable at their central portions by slip joint connections and extending to a point on the ground under the ends of the foot rail of the bed, supporting bars pivoted to the side rails below the slip joint therein, castings secured in the angle between the flanges of the foot 110 rail at its ends provided with downwardly inclined projections making slip joint connection with the free ends of said supporting bars and flexible means connecting said foot bar and the lower end of the side rails. 115

5. The combination with a flexible bed bottom, of rigid end bars secured to said bottom across the ends, legs having easily released connection to one of said end bars for supporting it, side rails having easily 120

releasable connection to said end bar extending downwardly at an angle along said bed bottom and being of tubular form, a supplemental bar rounded in cross section but open to its full diameter along its under surface except at the free end fitting around the upper surface of each side rail and pivoted thereto at the upper end through longitudinally projecting side ears, means on that end bar above the lower ends of the side rails for making slip joint connection with the free ends of said supplemental bars, and flexible means connecting and adjustably tending to draw together the said end bar and the lower ends of said side rails.

6. The combination with a flexible bed bottom, of rigid end bars secured to said bottom, tubular downwardly inclined side rails each made up of two sections with a slip joint connection near the middle one end of one section having slip joint connection with one end bar and the other end of the other section being curved downwardly, a supplemental bar rounded in cross section over the top but open to its full diameter on the under surface except at its extreme free end where the lower opening is less than the diameter, fitting the upper surface of the lower section of each side rail to a point beyond the down curve and pivoted through side ear extensions to said sections at the upper end so that it may turn upwardly at an angle to said section, a pair of projections carried by the end bar over the lower ends of the side rails adapted to make slip joint connection within the semi-tubular ends of said supplemental bars.

7. The combination with a flexible bed bottom, of rigid end bars secured to said bottom, tubular downwardly inclined side rails each made up of two sections with a slip joint connection near the middle one end of one section having slip joint connection with one end bar and the other end of the other section being curved downwardly, a supplemental bar rounded in cross section over the top but open to its full diameter on the under surface except at its extreme free end where the lower opening is less than the diameter, fitting the upper surface of the lower section of each side rail to a point

beyond the down curve and pivoted through side ear extensions to said sections at the upper end so that it may turn upwardly at an angle to said section, a pair of projections carried by the end bar over the lower ends of the side rails adapted to make slip joint connection within the semi-tubular ends of said supplemental bars and adjustable tension means connecting said end bar and the lower ends of said side rails tending to move the end bar downward turning the supplemental bars on their pivots and thus placing tension on the bed bottom.

8. The combination with a flexible bed bottom, of transverse angle bars secured to the ends thereof, two castings secured to the angle bar at the head of the bed in the angle underneath the bar, each provided with a downwardly opening tubular socket and a tubular socket extending longitudinally of the bed, two tubular legs or supports removably fitting in said downwardly extending sockets at their upper end, two tubular side rails each being separable near the middle of a slip joint connection preventing relative rotation and each making detachable slip joint connection with said longitudinal sockets at their upper ends and being curved downwardly at the lower ends, automatic means for preventing said rails from turning in said sockets, a supplemental bar for each side rail pivoted at its upper end to said rail and rounded in section at its upper half but open to its full diameter along the bottom except at its lower end fitting said side rail from the pivot to its down curve and there having the bottom opening less than the diameter, two downwardly inclined projections secured to the angle bar at the foot of the bed adapted to fit and make slip joint connection with free ends of said supplemental bars when at such angle to the side rail as to properly elevate the angle bar and adjustable flexible means for connecting the angle bar at the post of the bed with the lower ends of the side rails under tension.

In testimony whereof we affix our signatures.

ARVID GUSTAFSON.
JAMES HENRY MURPHY.
